SYSTEM OF DENTAL PROTHESIS

Eduardo Villaseñor Olasaga and José Santiago
Trejo Solis, Mexico City, MexicoApplication November 7, 1940, Serial No. 364,720
In Mexico November 29, 1939

3 Claims. (Cl. 32—9)

The present invention, in general terms, is related to systems of dental prothesis and more particularly it refers to a system of artificial teeth, interchangeable, made of porcelain or of any other adequate material. This system offers great advantages over any thus far applied or known in the dental prothesis, not only due to the safeness and firmness which the artificial teeth acquire, but also on account of the completely natural aspect which they present.

Therefore, the main object of the present invention is to improve considerably the aspect relative to the adherence of the artificial teeth to the backings which may or may not be integral parts of the teeth.

Another aim of the invention is to provide the means which admit the application of the present system of artificial and interchangeable teeth fastened to backings, in combination with the well-known systems of adherence to the root of the teeth with pegs, so that the invention also allows the adaptation of the interchangeable backing system to that of the adherence to the root of the teeth by means of pegs.

Another purpose is to provide a system of adherence of artificial teeth to backings which, in addition to being more solid and durable, present a completely natural aspect without the possibility of any part of the metal of the backings being seen, not even when the mouth is opened. Thus, not only the firm attachment of the artificial tooth has been considered but also its natural and aesthetic appearance.

The above and some other advantages, purposes and characteristics of the invention will become apparent in the following description and drawings which as illustrations are included herewith. The same reference numbers in the drawing being used to indicate the same parts appearing in the different figures shown.

In the drawing:

Fig. 1 represents a lateral view of a tooth built in accordance with the present invention, backing to which the tooth is fastened being shown by the dotted lines.

Fig. 2 is a profile viewed from above of the backing which holds the artificial tooth tightly.

Fig. 3 illustrates a front elevation of the backing shown in Fig. 2.

Fig. 4 represents a transverse cut as indicated by the line E—F of Fig. 1.

Fig. 5 shows the profile of an artificial tooth provided with its corresponding backing as per this invention. This backing is adapted to be fastened to the root of the natural tooth by a

peg as is customary in the art of dentistry. The backing is indicated by dotted lines and the root by a vertical cut.

Fig. 6 is also a profile of the artificial tooth adjusted to its corresponding peg, a vertical cut being shown of the backing and indicating with dotted lines the outline of the artificial tooth and the root of the natural tooth.

The improved bi-partite artificial tooth includes a tooth proper or facing and a backing, to which the facing is secured, to present a solid durable interlocking relation, with a completely natural aspect, while the backing in assembled relation is completely concealed.

The backing, indicated generally at 15, is an integral body of metal or other appropriate material. The front face of the backing—that face next the tooth proper—is formed with a vertically-ranging projection 16', the side edges of which are undercut at 17', see Figure 4. The upper end of the projection 16' is extended forwardly and increased in width to form what may be termed a locking head 17, the forward face of which curves downwardly and rearwardly. The lower edge of the head 17 is adjacent its juncture with the projection 16' upwardly cut away transversely or recessed, as at 17^a, thus providing a depending lug-like appendix 18 of the full width of the head 17 and spaced from the projection 16'. The lower end of the projection 16' is slightly rounded, as at 24, Figure 6, and the side edges of the backing from which the projection 16' extends are outwardly and rearwardly rounded or undercut, as at 15^a on opposite sides of such projection, thus forming a relatively narrow neck connecting the projection 16' with the body of the backing, as clearly shown in Figure 4.

The facing or tooth proper, indicated generally at 10, is formed on its rear or backing-engaging face, with a recess 10^a to receive the projection 16', the edges of the recess extending inwardly to accurately fit in the reduced neck portion 15^a of the backing to interlock the parts, as at 20, Figure 4. This, it will be apparent, insures an accurate interlocking between the tooth proper and backing to prevent any relative forward, rearward or lateral movement. Forwardly of the recess 10^a, at the upper end and communicating therewith, is a channel 30, shaped to accurately receive in a close fit the locking head 17 of the backing 15. The lower end of channel 30 is formed to provide a depression 31 to accurately receive and fit the appendix 18 of the backing. The lower end of the

recess 10^a in the tooth facing 10 is shaped to form an accurate seat for the rounded end 24 of the backing projection 16'. The rear face of the tooth facing 10 is rounded rearwardly and outwardly as at 31 to accurately fit the complementary surface of the backing, as more particularly shown in Figure 4.

The facing 10 is fitted to the backing 15 from beneath, and when properly cemented in place, the various parts interfit, as clearly shown in Figures 1 and 2. It will be noted that the interfitting is such that the tooth facing is interlocked against relative upward movement, which of course is the direction of stress in the use of the tooth, and furthermore, the facing 10 is so interfitted with the backing 15, that no part of the latter is visible from the front of the tooth. The upper surface 22 of the backing is concave and the upper surface 24 of the facing is coincidentally concave, shaped to adapt itself perfectly to the alveolus of the user.

The backing 15 here described has been formed substantially so as to present a socket forming an independent unit from the bridge support, thereby making it possible the adaptability of teeth held with pegs 25 and fastened to the natural root 26 of the tooth that has been removed. Thus, to this end, the said peg is 25 screwed by means of its thread to 27 the backing 15 as illustrated in Figs. 5 and 6 of the attached drawing.

Thus far, I have described and illustrated the preferential manner of carrying this invention into practice, but I wish to state here that it is not my desire to limit my rights of invention to the illustrations and descriptions made here about it, but, due to the different changes and

variations which may arise when carrying this invention into actual effect, my rights must be considered within the reach of the stipulations mentioned in the following chapter regarding claims.

Having thus described the invention, what we consider as new and desire to secure by Letters Patent is:

1. A bi-partite tooth structure, including a backing and a tooth facing, the backing having a vertical projection enlarged at the upper end forwardly and laterally to provide a locking head, the lower end of the head having a depending appendix in advance of and spaced from said projection, the tooth facing being formed with a complementary recess in its rear face to accurately receive and fit the locking head, appendix, and projection of the backing, the recess of the facing opening through the upper end of such facing to permit the facing and backing to be assembled by relatively direct upward movement of the facing, said formation limiting such relative upward movement to a predetermined relation of the backing and facing.

2. A construction as defined in claim 1, wherein in the side edges of the projection on the backing are undercut, and wherein the complementary recess in the facing is formed to interfit with such undercut edges of the backing.

3. A construction as defined in claim 1, wherein in the locking head of the backing is, when the facing and backing are assembled, in substantially vertical alignment with the biting edge of the facing to afford maximum resistance in the use of the tooth.

EDUARDO VILLASEÑOR OLASAGA.
